UNITED STATES PATENT OFFICE.

HENRY WIEDERHOLD, OF PHILADELPHIA, PENNSYLVANIA, ASSIGNOR TO THE BARBER ASPHALT PAVING COMPANY, OF PHILADELPHIA, PENNSYLVANIA, A CORPORATION OF WEST VIRGINIA.

APPLICATION OF BITUMINOUS LININGS TO CONCRETE SURFACES.

1,259,337.

Specification of Letters Patent. Patented Mar. 12, 1918.

Application filed January 2, 1915. Serial No. 207.

To all whom it may concern:

Be it known that I, HENRY WIEDERHOLD, of Philadelphia, in the county of Philadelphia and State of Pennsylvania, have invented certain new and useful Improvements in the Application of Bituminous Linings to Concrete Surfaces, whereof the following is a specification.

For the purpose of applying a bituminous lining to a concrete wall, I have invented a process by which the proposed bituminous lining is poured while hot and liquid into the interspace between the concrete wall and a temporary supporting surface, which is removed after the bituminous lining has set. In the practice of this process however it is essential that the supporting surface shall not adhere to the bituminous substance when set, and to prevent such adhesion I provide the supporting surface with a paint which accomplishes this end.

The supporting surface is erected substantially parallel to the wall to be lined, leaving an interspace of the thickness desired for the lining. The supporting surface may be formed either of metal or wood, and in either instance my paint is applied thereto, prevents any adherence of the supporting surface to the bituminous lining.

The accompanying drawing illustrates the practice of my process. It shows a concrete wall 1, to which the bituminous surface or lining is being applied. For this purpose uprights 2, are provided, which in turn maintain in place a temporary supporting surface or mold wall 3, say of boards. To the surface of this mold wall opposing the concrete wall 1, is applied my paint 4, while 5, represents the bituminous lining as poured between the concrete wall and the mold wall. Ordinarily the mold wall is built up to a

convenient partial height, and the bituminous lining poured to nearly that height and allowed to set. The mold wall is then built up higher and another layer of the bituminous lining applied, and so on until the lining is complete.

I prepare my paint by taking ordinary soft soap and adding to it sufficient water to make a soft paste. This paste is then applied to the desired surface by means of a brush. After the supporting surface is coated and put in place bituminous lining is poured while hot and liquid into the space between this supporting surface and the concrete wall. In this position it sets and when cooled the temporarily supporting surface is removed. Owing to the use of this paint there is not only no adhesion rendering the removal of the supporting surface difficult, but the bituminous lining which has set against it, presents a smooth and glossy surface.

Having thus described my invention, I claim:

The process of applying a bituminous lining to a concrete wall, which consists in covering the surface of a temporary mold wall adjacent to the concrete wall with a paste composed of soft soap and water; pouring a bituminous mastic while hot and liquid into the interspace between the mold wall and the concrete wall; and removing the mold wall after the bituminous mastic has cooled.

In testimony whereof, I have hereunto signed my name, at Philadelphia, Pennsylvania, this thirtieth day of December, 1914.

HENRY WIEDERHOLD.
